United States Patent Office.

HENRY A. LUDWIG, OF NEW YORK, N. Y.

Letters Patent No. 97,940, dated December 14, 1869.

IMPROVEMENT IN FURNACES FOR THE MANUFACTURE OF ULTRAMARINE.

The Schedule referred to in these Letters Patent and making part of the same

To all whom it may concern:

Be it known that I, HENRY A. LUDWIG, of the city, county, and State of New York, have invented a new and useful Improvement in Furnaces for the Manufacture of Ultramarine, of which the following is a full, clear, and exact description, reference being had to the accompanying drawing, forming part of this specification, and in which—

Figure 1 represents a centrally vertical longitudinal section of a double oven, constructed in accordance with my improvement, and

Figure 2, a vertical transverse section thereof, through the line xx in fig. 1.

Similar letters of reference indicate corresponding parts.

My improvement has reference to the manufacture of artificial ultramarine, and though more particularly designed for making that article from a mixture or compound which I regard as superior to any other for the purpose, and which is made the subject of a separate application for Letters Patent, said invention is not restricted thereto, but may be used for making the article from other compounds, such as, for instance, the mixtures ordinarily used.

Heretofore it has been customary to place the compound or mixture in crucibles, and gradually heat up the same, till acquiring a red heat, for a lengthened period, in a suitably-constructed oven, and afterwards withdraw the crucibles from said oven, and taking out the fused or partly fused mass, subsequently to suitably pound or prepare it, and then place the same in a second oven, heated, by a separate fire, to a lower temperature than the first oven, for a sufficient length of time to desulphurize the mass, that afterwards is properly and variously treated.

In thus using separate ovens, heated by separate fires, there is not only great waste of fuel, and much labor in attending to the fires, but the process of making ultramarine in large quantities is necessarily a slow one.

My improvement obviates these difficulties; and

The invention consists in a peculiar construction of furnace, embracing two ovens, heated, by a single fire, to different temperatures, to carry out the treatment of the mass as hereinbefore recited.

Referring to the accompanying drawing—

A represents the fire-place of the furnace, arranged to occupy a central position, and opening in front.

B is a lower, and C, an upper oven, both heated by or from the same fire, the heat and gaseous products of combustion first passing directly from the fire-place up into the oven B, through a longitudinal central

opening, a , made in the bottom of said oven, and, after disseminating, through the latter among the crucibles containing the mass to be treated, escaping, by side-flues b , from or near the bottom of said lower oven, up into the upper oven C, and thence, through end-openings c in the roof of the latter, into an escape-flue or passage, D.

These crucibles containing the mass are first put into the lower and hottest oven B, on either side of the central opening a , and having thus been exposed to the requisite high temperature for a sufficient length of time, (the heat gradually increasing, and afterwards subsiding,) are taken out of said oven B, and the mass, after having been pounded or prepared, put in iron vessels, within the upper and cooler oven C, or spread out on the bottom of said oven, for the purpose of desulphurization, and where it is allowed to remain while a fresh charge of the compound or mixture is undergoing fusion or treatment in the lower oven B, so that the one fire serves to keep both ovens at their proper relative temperatures, and much time and labor is saved, the desulphurizing-process of a previous charge going on at the same time that a new charge is being fused or treated in the lower and hotter oven; nor need the furnace be opened, to take out the charge from the upper oven, till the charge in the lower oven has been fully and properly treated.

In this way is secured not only economy of fuel, but a much larger quantity of material may be treated in a given time, and with less labor.

Furthermore, the manner in which the heat is introduced into the lower oven, and divided up in its escape therefrom, on opposite sides, by the flues b , from the bottom of said oven to opposite sides of the upper oven, added to the arrangement of the ovens one above the other, insures an equalizing action of the heat on the masses in the two ovens, at a proper relative temperature, as regards said ovens, the upper one of which is heated, in part, by radiation from the roof of the lower one.

What is here claimed, and desired to be secured by Letters Patent, is—

The combination and arrangement, in the one furnace, of the central fire-place A, the ovens B C, the side-flues b , and the outlet or outlets c to the escape-flue or passage D, substantially as and for the purpose herein set forth.

HENRY A. LUDWIG.
